UNITED STATES PATENT OFFICE

JOSE FERNANDEZ, OF BROWNSVILLE, TEXAS.

SELF-FILLING TIRE.

1,200,418.

Specification of Letters Patent.

Patented Oct. 3, 1916.

Application filed April 20, 1915. Serial No. 22,655.

To all whom it may concern:

Be it known that I, JOSE FERNANDEZ, a citizen of the United States, residing at Brownsville, in the county of Cameron and State of Texas, have invented new and useful Improvements in Self-Filling Tires, of which the following is a specification.

This invention relates to tire inflating mechanism and the principal object of the invention is to provide simple and efficient means for automatically inflating the tire by the action of the weight of the vehicle as the same progresses over the road.

Another object of the invention is to provide a device of this character employing a pump having a piston actuated by the weight of the vehicle and which is so connected that without springs or other intermediary mechanism it will be returned to normal position after every stroke.

Further objects of the invention will appear as the following description is read in connection with the accompanying drawing, which forms a part of this application, and

in which:—

Figure 1 is a detail side elevation of the wheel showing the apparatus applied thereto. Fig. 2 is a sectional view taken on the line 2—2 of Fig. 1. Fig. 3 is a horizontal sectional view taken on the line 3—3 of Fig. 1 and looking in the direction of the arrow.

Referring more particularly to the drawing, 1 represents an ordinary wheel felly having secured thereto the tire receiving rim 2 in which the ordinary clincher shoe or casing 3 is secured. This casing contains the usual inner tube 4 which in this instance has connected thereto and passing through the felly and rim in place of the valve an elongated nipple 5 to the outer end of which is secured the thickened bottom 6 of a pump cylinder 7. The bottom 6 is provided with a gland collar 8 externally threaded to receive the packing washer 9 which bears directly against the outer face of the felly, as shown, and holds all parts in operative position. The outer end of the cylinder 7 is closed by a cap 10 having a thickened central portion 11 in which the valve seat 12 is formed. This valve seat communicates with an inlet port 13 which is closed by the valve 14 and normally held in such position by the spiral spring 15 surrounding its stem. Covering the enlarged portion or boss 11 is a foraminous cap 16 which contains a quan-

tit of wire gauze or any other suitable dust collecting material 17.

Slidably mounted within the cylinder 7 is a piston head generally indicated at 18 and consisting of a central plate 19 centrally apertured and formed with the valve seat to receive the valve 20. On opposite sides of the central plate are arranged packing disks 21 held in place by the plates 22 and the screws 23 which also connect the piston head with a cross plate 24 of slightly less wider diameter than the diameter of the opening 25 immediately above the valve 20. The cross plate 24 has connected directly thereto a plunger or piston rod 26 which passes through the nipple 5 and has formed on its outer end a ball 27 fitted for universal movement in the socket member 28 which is connected to the outer or peripheral portion of the inner tube 4 by means of a clamping plate 29 and screw 30.

It will be seen from the foregoing that at each revolution of the wheel the piston will move the piston head inwardly toward the valve 14. The air in the cylinder between the piston head and the valve 14 will be compressed and will pass through the valve 20 and through the nipple 5, which the piston 26 loosely fits, into the inner tube. Immediately that the weight is removed from the piston 26 it will be restored to normal position by the inner tube which will expand the casing to its normal position until again compressed by the weight of the vehicle.

It is of course understood that a device of this character is ineffective to start the insulation of a completely deflated tire and for this reason the valve 31 is threaded into the bore 32 formed in the thickened end 6 of the cylinder 7. This valve is of the ordinary air pump type valve commonly employed in pneumatic tires and has its outer end closed by the usual dust cap.

What is claimed is:—

In a device of the class described in combination a felly, a tire, a rim secured to the felly and receiving the tire, said felly and rim being formed with an opening, an elongated nipple, a piston rod projecting through said opening and universally connected in the tire, a clamping member engaging said threaded nipple at one end for jamming the base of said tire against said rim, a packing nut of a greater diameter than said nipple surrounding the same and

engaging said felly, said nipple projecting through said felly and rim in spaced relation thereto and having a bore of greater diameter than said rod, said rod projecting through said nipple, a piston secured to said rod, a pump cylinder having a projecting gland collar with an opening communicating with the opening in the gland collar, said packing washer being formed with a 5 circular depression in which said collar is received, said nipple being threaded into 10

said collar and the opening of said pump cylinder whereby to jam said collar against said washer, whereby the opening of the nut provides clearance between the washer 15 and nipple.

In testimony whereof I affix my signature in presence of two witnesses.

JOSE FERNANDEZ.
